UNITED STATES PATENT OFFICE

160,363

MEASURING DEVICE

Orson D. Brehman, Torrance, Calif.

Application March 14, 1949, Serial No. 1,397

Term of patent 14 years

(Cl. D52—1)

To all whom it may concern:

Be it known that I, Orson D. Brehman, citizen of the United States of America, residing at Torrance, in the county of Los Angeles, State of California, have invented a new, original, and ornamental Design for a Measuring Device, of which the following is a specification, reference being had to the accompanying drawing, forming a part thereof.

Fig. 1 is a side elevational view of a measuring device, showing my new design.

Fig. 2 is a plan view of the device; and

Fig. 3 is a side elevational view of the reverse side of the device shown in Fig. 1.

I claim:

The ornamental design for a measuring device, substantially as shown.

ORSON D. BREHMAN.
